WOUND PACKAGE OF YARN AND METHOD AND MECHANISM FOR PRODUCING THE SAME

George White, Nuneaton, England, assignor to Courtaulds Limited, London, England, a British company

Application June 27, 1941, Serial No. 400,086
In Great Britain September 20, 1940

12 Claims. (Cl. 242—43)

This invention relates to wound packages of yarn on single-flange bobbins and to a method and mechanism for producing such packages, and one of its objects is to produce a package of yarn wound on a single flange bobbin such that the yarn can be readily unwound over the flangeless end of the bobbin and also has little tendency to slough off the bobbin.

It is already known, when producing a package of yarn, to reciprocate the yarn guide over a uniformly long traverse while increasing the speed towards its upper limit.

According to the present invention, a package of yarn comprising a single-flanged bobbin and yarn wound thereon is produced in which the layers near the flanged end are of slight pitch winding, or as it is frequently expressed, parallel wound, while the layers near the flangeless end vary in respect of both pitch and traverse from layers of a steep pitch winding toward the flangeless end of the bobbin to layers of a lesser pitch winding terminating at an appreciable distance from the flangeless end.

Mechanism by which it is possible to obtain a package with the layers arranged as above described is illustrated in the accompanying drawings, in which Figure 1 is an elevation of traverse mechanism; Fig. 1A is a detail view in elevation of portion of the operating mechanism shown in Fig. 1; Figure 2 illustrates in cross-section a bobbin which has been wound with the help of such mechanism.

Figure 3 corresponds to the traverse 1 of Figure 2 in which only the slow traverse is actuating the thread guide.

Figure 3A corresponds to the traverse 5 of Figure 2 and shows a slow traverse over part of the bobbin and an accelerated traverse over a further part.

Figure 3B corresponds to the traverse 10 of Figure 2 and consists of a small portion at a slow traverse and the remainder at an accelerated traverse and then the reverse process occurs.

Fig. 4 is a sectional view drawn to a larger scale, of the operating cam shown at the left in Fig. 1.

In Figure 1, A represents the main operating cam on which rests the roller C attached to the upright lever D which is fulcrumed at E. The roller C is kept in contact with the cam A by means of the spring D' secured to the lever D and to the frame (not shown). The lever D is provided with a long slot by which the length of the traverse can be adjusted, and in this slot is carried and fixed at any selected position the

stud G on the end of the connecting rod F. The other end of the connecting rod F passes through two adjusting brackets which are bolted to the bar H. At the other end of the bar H is a stud N on which swings a second upright cam lever L. The top of the lever L is connected through the stud P to the rod Q, which in its turn is connected to the traverse rod Y running the full length of the machine. On the traverse rod Y are mounted the thread guides Z and the thread A runs over the guide Z to the bobbin B. At the bottom of the lever L is an adjustable bracket R carrying the cam roller S. A spring K is provided attached at one end to a point in the lever L adjacent to the stud P and at the other end to a suitable hook attached to a bracket J at the other end of the bar H. The said bar H also is provided with an adjusting bracket M against which the spring K tends to hold the lever L. A heart-shaped cam T is provided so that the roller S at the lower end of the lever L tends, on each reciprocatory movement of the mechanism caused by the rotation of the cam A to come into contact with the heart cam T, and the relative positions of the roller S and the cam T are so adjusted that at the end of the stroke of the bar H the roller S just comes into contact with the portion of the cam nearest to its centre of rotation. The cam T is caused to rotate slowly by means of a pawl W acting on the ratchet wheel U secured to the cam T. This pawl W is mounted on an upright lever V, provided with a movable finger E pivoted on the stud F' at the upper end of the lever V. The movable finger E has its lower end held against the stud G by the spring H' one end of this spring being attached to the lower end of the finger E and the other to the lever V. Mounted on the rod Q is a bracket J which will also carry a rod K which is adjustable in a vertical direction and fastened to the bracket J by a screw. At the lower end of the rod K is mounted a hardened steel roller L which is free to revolve.

In the operation of the machine, the roller L when moving from right to left, comes up against the highest point of the finger E and moves the finger E, the lever V and the pawl W along to the left to a predetermined extent, until the angle of the lever V is such that the roller L passes over the top of the finger E. The lever V is then brought back to its original position by a spring (not shown). The pawl W has an edge which is designed to engage in the ratchet wheel

U when the pawl is moved to the left, but disengages when moving to the right.

When the roller L is moves from left to right, it strikes the sloping surface of the top of the finger E, and E is depressed around its fulcrum F until the roller L has passed over, then the finger E, under the influence of the spring H, resumes its position.

The specific construction for operating the lever V, as shown in Fig. 1A, forms no part of the invention and is merely illustrative of the manner in which the ratchet may be moved by the traverse bar. The ratchet wheel U can suitably be rotated one whole revolution while the cam wheel A is rotated 60 times. When the roller S strikes any other part of the cam T than that part which is nearest to the axis, the upper part of the lever L is given a further movement to the right, such movement being controlled by the spring K. It is thus obvious that at such times, the rod Q, which is directly attached to the traverse mechanism is given an extra movement, in addition to that caused by the cam A, and the traverse guide through which the yarn runs on the bobbin is given an accelerated speed.

In Figure 2, which illustrates in cross-section a bobbin wound with yarn, a line diagram is shown illustrating the build of the yarn on the bobbin. In this diagram, a continuous line is used to denote a slow traverse speed resulting from the action of the cam A only, when the lever L has not been given any additional motion by means of the cam T. A dotted line is used to denote an accelerated traverse speed resulting from the combined actions of the two cams A and T. For the sake of convenience, the line diagram has been drawn on the assumption that the cam A executes only 20 revolutions while the cam T revolves once. The cam A is driven at a constant speed through gearing from the bobbin pulley shaft, and when the cam T is in the position shown in Figure 1, only a slow traverse of length $a+b$ is imparted to the traverse-guide, this first traverse being represented in length and speed by the top line marked 1. At each complete oscillation of the traverse-guide, the cam T is turned through a small angle by means of the pawl W, so that commencing from the position shown in Figure 1, the roller S will at each successive traverse meet the cam T a little sooner until after ten traverses, the peak of the cam T is reached. From this point onwards the reverse procedure takes place and the cam T meets the roller S later and later until the cam T is again at the position shown in Figure 1. Assuming that the cam A rotates with constant speed and ignoring any slight alteration in its position which may be imparted to it as herein-after described, the fulcrum-stud N and the part of the lever L immediately adjacent to it will move left and right at a constant speed and over a constant distance. With the cam T in the position shown in Figure 1, the roller S only just reaches the cam T when the roller C reaches the peak of cam A. As cam T is turned, the roller S meets it at an earlier point and the lever L is swung about its fulcrum N through an increasing distance and the traverse is thereby lengthened until the cam T has rotated through 180° . While the traverse is under the additional control of the cam T, the speed of the traverse is, when using the apparatus more particularly illustrated in Figure 1, approximately doubled. In the line diagram, the lines marked from 2 to 10 respectively represent the traverse of the sec-

ond to the tenth traverses. Taking for example line 2 as representing the traverse when the cam T has been turned a small amount, the roller S comes into contact with the cam T when nearing the end of the traverse, so that the last small portion is lengthened and is faster. As the cam T continues its rotation, this last portion is gradually increased until the peak of T is facing S; then the line 10 would represent the traverse and S would only have moved a small amount a to the right before coming into contact with the peak of T. Then as the fulcrum N continues to move forward, the traverse receives its maximum movement over the distance $b+c$ at the faster speed. After the peak of T is passed, the traverse gradually shortens and works back up to the shortest traverse length $a+b$ and this steady increase and decrease continues.

Although as previously stated, the above description assumes that the cam A is not reciprocated bodily along its axis by a small amount, it is generally preferred to employ the well known device, known as a plate-cam, shown at B, for causing such reciprocation through a distance of say one tenth of an inch; such reciprocation may conveniently take place once in 18 or 20 revolutions of the cam.

This device is illustrated in Figure 4, in which the cam A is carried by a wheel M provided on its circumference with cogs N and rotating freely on the extended axle O of a second wheel P provided on its circumference with cogs Q. The face of the wheel P is provided with an undulating cam B against which rests the cam follower R. The cogs N of wheel M and Q of wheel P both engage a freely running cog wheel S. Wheel P is keyed to, and driven by, a shaft T and permits motion through the cog wheel S to the wheel M. The number of cogs on wheel M is not the same as the number of cogs on wheel P, but may conveniently be one more or one less, so that wheel M will rotate at a slightly different speed from wheel P and consequently the cam follower R will move slowly along the cam B and wheel M, and together with cam A will have a small and slow movement alternately towards and away from the fixed wheel P.

In carrying out the present invention, it is preferred to employ a bobbin which has a slight lip at the flangeless end, and of which the diameter of the core at the flangeless end is somewhat greater than that at the flanged end.

What I claim is:

1. Traverse mechanism for use in winding yarn on to a single-flanged bobbin comprising a thread guide arm, a main cam, an auxiliary cam and means actuated by the main cam to give a slow traverse speed and by the main cam and an auxiliary cam to give an accelerated traverse speed, said actuating means including means for rotating the auxiliary cam at a fraction of the speed of the main cam and thereby causing the additional traverse speed to increase to a maximum and fall to a minimum alternately so that the layers of yarn near the flanged end of the bobbin are substantially parallel wound and the layers of yarn near the flangeless end of the bobbin are of a comparatively steep pitch winding.

2. Traverse mechanism for use with a traverse bar in winding yarn on to a single-flange bobbin, comprising a cam motion, a cam surface, and means causing slowly advancing and receding of said surface, a rod reciprocated by said cam mo-

tion in the direction of its length, a second rod pivoted in a direction more or less perpendicular to the first rod, one end of the said second rod being connected to the traverse bar, while the other end is adapted to advance toward and recede from said surface so that when the said other end of the second rod meets the said surface, the end of the second rod, which is attached to the traverse bar, is given an additional motion to that which is imparted to it by the reciprocating first bar.

3. Traverse mechanism for winding yarn on to a single-flange bobbin, comprising a lever, a main cam adapted to reciprocate said lever, a bar, a connecting rod adjustably secured at one end to the lever and at the other end to said bar, a second lever pivoted intermediate its ends to the said bar and normally held in fixed relation thereto by a spring, an auxiliary cam mounted relative to one end of the said second lever means 20 for driving the said auxiliary cam to contact a roller on said end once during each reciprocation of the said first lever whereby the said second lever is moved relatively to the said bar by an amount varying from zero to a maximum, a 25 rod secured to the other end of the said second lever, a traverse rod secured to said rod, and a number of thread guides secured to the said traverse rod.

4. Traverse mechanism as claimed in claim 3, 30 wherein the main cam is adapted to be reciprocated bodily during its rotation.

5. Traverse mechanism as claimed in claim 3, wherein the first mentioned lever is pivoted at one end and the connecting rod has a stud at one 35 end secured in a predetermined position in a slot in the said first mentioned lever.

6. Traverse mechanism as claimed in claim 3, wherein the second lever has a slot intermediate its ends for the reception of a stud on the end 40 of the bar, and means for securing the said stud at any desired point in the said slot.

7. Traverse mechanism as claimed in claim 3, wherein the auxiliary cam is heart-shaped.

8. Traverse mechanism as claimed in claim 3, wherein the auxiliary cam is secured to a ratchet wheel adapted to be turned by a pawl at a speed less than that of the main cam.

9. Traverse mechanism as claimed in claim 3, in combination with a spring and an adjustable bracket on the bar wherein the second lever is normally held by the action of said spring against 10 said bracket.

10. A package of yarn comprising a single-flange bobbin and yarn wound thereon, the layers near the flanged end being of slight pitch winding, and the layers near the flangeless end varying in respect of pitch and traverse from layers of a steep pitch winding toward said flangeless end of the bobbin to layers of a lesser pitch winding at some distance from the flangeless end.

11. A wound package of yarn on a single-flanged bobbin in which the layers of yarn near the flanged end of the bobbin are substantially parallel wound and the layers of yarn near the flangeless end of the bobbin vary in respect of both pitch and traverse from layers of a steep pitch winding approaching the flangeless end of the bobbin to layers of a lesser pitch winding terminating at an appreciable distance from the flangeless end.

12. Traverse mechanism for winding yarn on to a single flange bobbin comprising a thread guide, means for operating said thread guide for winding the layers near the flanged end with slight pitch and means for varying the operation of said thread guide operating means for winding the layers near the flangeless end varying in respect of pitch and traverse from layers of a steep pitch winding toward said flangeless end of the bobbin, to layers of a lesser pitch winding at some distance from said flangeless end.

GEORGE WHITE.
